CHECKSTAND

Charles R. Larson, Bellevue, Mich., assignor to Hapman
Conveyors, Inc., Kalamazoo, Mich., a corporation of
Michigan

Filed July 13, 1959, Ser. No. 56,752

Term of patent 14 years

(Cl. D80—2)

Fig. 3

Fig. 4

Figure 1 is a front perspective view of a checkstand embodying the new design.

Figure 2 is a rear perspective view thereof, showing the sliding shelf in an extended position.

Figure 3 is a top plan view thereof.

Figure 4 is a rear elevational view thereof, showing the sliding shelf in an extended position.

Figure 5 is a front elevational view thereof.

Figure 6 is an elevational view of one end thereof.

Figure 7 is an elevational view of the other end thereof.

The kick panel is lined to indicate contrast.

I claim:

The ornamental design for a checkstand, as shown and described.
